UNITED STATES PATENT OFFICE.

WALTER M. BETHUNE, OF TALBOTTON, GEORGIA, ASSIGNOR OF ONE-HALF TO B. M. HALL, OF TALBOTTON, GEORGIA.

SAFETY ATTACHMENT FOR GUNS.

SPECIFICATION forming part of Letters Patent No. 772,495, dated October 18, 1904.

Application filed March 22, 1904. Serial No. 199,401. (No model.)

To all whom it may concern:

Be it known that I, WALTER M. BETHUNE, a citizen of the United States, residing at Talbotton, in the county of Talbot and State of Georgia, have invented certain new and useful Improvements in Safety Attachments for Guns; and I do declare the following to be a full, clear, and exact description of the invention, such as will enable others skilled in the art to which it appertains to make and use the same, reference being had to the accompanying drawings, and to the letters of reference marked thereon, which form a part of this specification.

This invention relates to new and useful improvements in safety attachments to guns to prevent accidental discharge of the same; and the object of the invention is to produce means whereby a gun may be prevented from being fired excepting when pressure is applied to the stock end thereof simultaneously with the pulling of the trigger.

My invention consists in various details of construction and in combinations and arrangements of parts, which will be hereinafter fully described and then specifically defined in the appended claim.

I illustrate my invention in the accompanying drawings, which, with the letters of reference marked thereon, form a part of this application, and in which—

Figure 1 is a side elevation of a gun, showing my improvement as applied thereto. Fig. 2 is a vertical longitudinal section through a portion of the stock and locking mechanism, and Fig. 3 is a sectional view showing a slight modification in the construction of my safety apparatus.

Reference now being had to the details of the drawings by letter, A designates the stock of a gun which is of the general construction of a well-known gun, and said stock is provided with the usual lock mechanism in breech-loading guns, and B designates a sear-releasing bar which is pivoted to a link C upon a pin D, and to said pivotal lever C my attachment is connected, which comprises a rod E, having an eye E' fitting over the upper portion of said pivotal link C and adapted to push

the upper end of said lever C forward for the purpose of retracting the bar B out of the path of the sear, whereby the trigger may be pulled and the gun fired. Hinged to the stock end of the gun is a shoulder-piece H, hinged at H', and a buckskin or other suitable covering fabric (designated in the drawings by letter K) is placed over the opening between said shoulder-piece and the stock. The rear end of said rod E has a bearing at H² in a concaved recess in the inner face of the shoulder-piece H and passes through an aperture in the plate N, which is fastened to the end of the stock, and a spring Q is mounted upon said rod and bears against the shouldered portions thereof, and the object of said spring is to normally hold the shoulder-piece in the position shown in Fig. 2 of the drawings and to be under compression when the shoulder-piece is thrown toward the end of the stock.

Referring to Fig. 3 of the drawings, it will be seen that I have shown a slight modification of my apparatus in which provision is made for detaching the rod from the sear-actuating lever, in which the rod E is provided with two lugs E', projecting from the rod, near one end thereof, and spaced apart, said lugs being adapted to be thrown one on either side of the lever C, whereby as the rod is actuated longitudinally said lever may be tilted upon its pivot, and when it is desired to disconnect the rod from the lever said rod may be given a partial movement, so as to throw the lugs away from the lever and allow the rod to move independent of said lever. In the modification shown a neck h projects through the butt-end of the gun and has a head h' thereon, whereby said rod may be easily given a partial rotary movement.

The operation of my invention is as follows: In the normal position of the parts, as illustrated in Fig. 2, the bar B is so positioned as to prevent the hammer from being released to fire a cartridge or shell, it being necessary to apply pressure to the shoulder-piece simultaneously with the pulling of the trigger, which would usually happen only when a gun is raised to the shoulder of a per-

son and in the act of being fired. As pressure is applied to the shoulder-piece the gun may be readily fired.

While I have shown a particular construction of apparatus illustrating the features of my invention, it will be understood that I may alter the same, if desired, as to details of construction without in any way departing from the spirit of the invention.

Having thus fully described my invention, what I claim as new, and desire to secure by Letters Patent, is—

A safety attachment for guns comprising, in combination with the stock, a trigger-re-

leasing-mechanism bar, a pivotal lever connected to said bar, a reciprocable bar connected to said lever for locking and releasing the trigger, a rotatable spring-pressed rod mounted in the stock of the gun, lugs projecting from said rod to engage either side of said lever, and a shoulder-piece bearing against said rod, as set forth.

In testimony whereof I hereunto affix my signature in presence of two witnesses.

WALTER M. BETHUNE.

Witnesses:

J. M. HEATH,
A. S. OWEN.
